GROCERY CART STERILIZER

Charles G. Carter, Knoxville, Tenn.

Application June 20, 1957, Serial No. 46,665

Term of patent 14 years

(Cl. D83—1)

Fig. 2

I claim:

The ornamental design of a grocery cart sterilizer, as shown and described.
